UNITED STATES PATENT OFFICE

157,441

SMOKER'S DESK SET

Frank J. Schroeder, Rochester, N. Y.

Application April 14, 1949, Serial No. 1,980

Term of patent 7 years

(Cl. D74—1)

To all whom it may concern:

Be it known that I, Frank J. Schroeder, a citizen of the United States of America and resident of Rochester, in the county of Monroe and State of New York, have invented a new, original, and ornamental Design for a Smoker's Desk Set, of which the following is a specification, reference being had to the accompanying drawings, forming part thereof.

Fig. 1 is a side elevational view of a smoker's desk set, showing the new design;

Fig. 2 is a top plan view thereof;

Fig. 3 is an end elevational view thereof, as seen from the right end of Figs. 1 and 2.

The side not shown in Fig. 1 is substantially the same as the one shown.

I claim:

The ornamental design for a smoker's desk set, substantially as shown and described.

FRANK J. SCHROEDER.
